US00D335291S

United States Patent [19]

Schnell

[11] Patent Number: Des. 335,291

[45] Date of Patent: ** May 4, 1993

[54] COMBINED VACUUM PUMP AND COMPRESSOR

[75] Inventor: Manfred Schnell, Schopfheim, Fed. Rep. of Germany

[73] Assignee: Mannesmann AG, Düsseldorf, Fed. Rep. of Germany

[**] Term: 14 Years

[21] Appl. No.: 653,439

[22] Filed: Feb. 4, 1991

[30] Foreign Application Priority Data

Aug. 2, 1990 [DE] Fed. Rep. of Germany M9005129.7

[52] U.S. Cl. D15/7

[58] Field of Search D15/7-9.2; 417/83, 187, 188, 360, 462, 552, 390, 410, 900

[57] CLAIM

The ornamental design for a combined vacuum pump and compressor, as shown.

DESCRIPTION

FIG. 1 is a perspective view of a combined vacuum pump and compressor showing my new design;

FIG. 2 is a front elevational view;

FIG. 3 is a rear elevational view;

FIG. 4 is a top plan view;

FIG. 5 is a bottom plan view;

FIG. 6 is a left side elevational view; and,

FIG. 7 is a right side elevational view.
